SMOKING COMPOSITION CONTAINING ALUMINA AND SMOKING UNIT CONTAINING SAME

Charles G. Albert, Basking Ridge, N.J., assignor to Minerals & Chemicals Philipp Corporation, a corporation of Maryland

No Drawing. Filed Feb. 12, 1960, Ser. No. 8,241

2 Claims. (Cl. 131—17)

This invention relates to smoking compositions and to smokable units including therein a novel particulate inorganic material mixed with the tobacco, the additive being capable of substantially reducing the quantity of tars normally generated during the burning of the tobacco and improving the aroma of tobacco. For many reasons, clinical and aesthetic, reduction in the tar yielded during the smoking of tobacco is highly desirable. First, there exists strong clinical, statistical and pathological evidence that certain constituents of tobacco smoke condensate (or "tars" as such condensate is usually termed) are potentially carcinogenic when deposited on human tissue. Secondly, aside from their alleged pathological effect, it appears that certain constituents of tars are responsible for the sharp irritating taste imparted to smoke from a cigarette or the like. Furthermore, tars produce disfiguring coloration of the teeth of many smokers, and if only for this reason, the lowering of total tars yielded during smoking is highly desirable.

Accordingly, it is a principal object of the instant invention to provide a tobacco composition which incorporates a novel aluminous additive which functions during the pyrolysis of the tobacco to reduce substantially the quantity of tars in the smoke effluent from said tobacco.

Another object of the invention is the provision of a composition including tobacco mixed with an innoxious aluminous additive capable at the elevated temperatures encountered in smoking tobacco of substantially lowering the yield of tars in the mainstream smoke of tobacco.

Other objects will be apparent from the description of the invention which follows.

I have discovered that when a small amount of a unique form of alumina, hereafter described, is mixed directly with smoking tobacco, the quantity of tar normally produced by a given weight of tobacco is reduced appreciably.

Stated briefly, tobacco compositions of the present invention comprise a uniform mixture of tobacco with a small quantity of finely divided microporous alumina which is produced by thermal decomposition of aluminum acetate. When such a tobacco composition is smoked, the amount of tar present in the mainstream smoke, that is, the smoke which passes through the mouth end of the smoking article containing the tobacco mixture, is reduced substantially from that produced by the same weight of tobacco but in the absence of the alumina. The smoke from such mixture is very mild and is considered very pleasant by smokers. The alumina I employ is innoxious and has no harmful effect on the smoker, even if it passes into the smoker's mouth.

It has been found, contrary to expectations, that the various aluminas produced by thermal decomposition of aluminum salts do not possess as a class the physical properties of the alumina obtained by ignition of aluminum

2

acetate and do not produce the same tar reduction when mixed with smoking tobacco. For example, thermal decomposition of aluminum tartrate results in an alumina which has little effect on the tar content of smoking tobacco when mixed therewith. Aluminas produced by thermal decomposition of aluminum salts other than aluminum acetate are outside the scope of my invention.

I am well aware that it has been suggested in the prior art to disperse in smoking tobacco various colloidal aluminas and hydrates of alumina as well as so-called "light alumina hydrate" in order to sorb various undesirable components of tobacco smoke. Activated bauxite, a form of amorphous alumina, has been suggested as a carrier for moisture or menthol. The specific form of alumina I employ differs profoundly in its physical and/or chemical characteristics from these as well as other aluminous materials suggested as tobacco additives. It has been found that many aluminas such as, for example, alpha-alumina trihydrate (bauxite) and alumina produced from alpha-alumina trihydrate by thermal activation, do not produce the desired tar reduction when mixed with tobacco. In fact, the latter form of alumina actually increases the amount of tar in the smoke produced by cigarette tobacco when it is uniformly mixed with the tobacco in the amount of 5% or 10% by weight. It is not presently understood why the alumina produced by thermal decomposition of aluminum acetate should have an effect on the combustion products of tobacco mixed therewith which is so different from the effect of alumina produced by thermal decomposition of a similar aluminum salt or from some highly sorptive alumina and aluminosilicates as, for example, the alumina produced by activation of alpha-alumina trihydrate.

The starting material I employ in the preparation of the novel aluminous tobacco additive substance is aluminum acetate or any of the basic aluminum acetates. For reasons of economy, I prefer to use the basic aluminum acetates, especially the basic diacetate, $\text{Al}(\text{OH})(\text{C}_2\text{H}_5\text{O}_2)_2$.

In preparing the novel form of alumina, aluminum acetate is ignited to oxidize completely the hydrogen and carbonaceous matter into volatile combustion products, leaving a white essentially pure anhydrous alumina residue which, after grinding, consists of white, fluffy, microscopic particles. These particles appear to be poorly ordered when examined under X-rays.

The alumina product has a B.E.T. surface area of about 110 to 150 square meters per gram. "B.E.T. surface area" refers to surface area of a product as determined by a nitrogen adsorption method described by S. Brunauer, P. H. Emmett, and E. Teller in their article entitled "Adsorption of Gases in Multi-Molecular Layers," on page 309 of Journal of the American Chemical Society, vol. 60, February 1938, using the molecular size data of H. K. Livingston presented in his article entitled "Cross-Sectional Areas of Molecules Adsorbed on Solid Surfaces," on page 569, Journal of the American Chemical Society, vol. 66, April 1944.

In igniting the basic aluminum acetate, a charred intermediate product is produced and ignition is carried out at a temperature and for a time sufficient to oxidize completely the hydrogen and carbonaceous matter. Calcining aluminum acetate in the presence of air (or other suitable form of available oxygen) at 1200° F. to 1500°

F. for a time sufficient to oxidize completely oxidizable matter in the starting material is recommended. The calcination time, which will vary with the furnace employed and the quantity of material being processed, will usually be for 1 to 24 hours. A suggested method of obtaining the desired alumina is to calcine basic aluminum diacetate for 2 hours in a muffle furnace held at 1400° F. After calcination, the product is ground to the desired particle size, usually 100% by weight finer than 325 mesh.

The tobacco I employ is conventional leaf tobacco of the type used in cigars, cigarettes or pipes. It is reasonable to expect that reconstituted tobacco or mixtures of tobacco leaf and reconstituted tobacco may be used.

In putting my invention into practice, the alumina powder obtained by decomposing aluminum acetate is uniformly mixed with tobacco leaf in amount of about 1% to 20%, and preferably 5% to 15%, based on the weight of the tobacco. Any method of uniformly dispersing the alumina powder on the tobacco particles may be employed and, inasmuch as the alumina particles are extremely small, they will adhere well to the tobacco without use of an adhesive substance. The additive may be applied by dusting the dry material on the tobacco, by spraying a dispersion of the additive in a liquid or gaseous carrier or by other means which will readily suggest themselves to those skilled in the art. Preferably, the tobacco to which the solid alumina additive is applied is in a form suitable for direct use in the cigarette or other smoking article for which it is intended, namely, tobacco which has been aged, shredded, humected and treated with flavoring agents and such other tobacco-treating materials as may be desired. If desired, an adhesive substance, inorganic or organic, may be employed to secure the finely divided alumina to the tobacco.

A filter tip integral with the column of the mixture of alumina and tobacco shreds may, if desired, form the mouth end of a cigarette of my invention. The filter tip may contain fine fibers or it may contain any microporous material which is used in a filter tip for a cigarette. The filter tip in a cigarette of the present invention will serve a plurality of important functions. It will supplement the tar reduction realized through the use of the alumina and it will prevent finely divided alumina particles from passing into the smoker's mouth.

The following examples are given to illustrate more fully my invention.

Tests were conducted to demonstrate that the total quantity of tar passing into the mainstream of the smoke from a given weight of cigarette tobacco is significantly reduced by mixing the tobacco with alumina which is produced by ignition of basic aluminum acetate. Similar

The calcined material was ground to 100% minus 325 mesh. The product was a white, fluffy powder having a B.E.T. surface area of 117 square meters per gram and consisting of a substantially pure form of alumina.

5 A blend of Turkish and domestic cigarette tobacco supplied under the trade name "Bugler" was used in all of the smoking experiments.

Experimental cigarettes were prepared by uniformly dry mixing 100 parts by weight of the tobacco shreds with 10 parts by weight of the alumina powder prepared from aluminum acetate and packing about 0.99 gram of this mixture (containing about 0.90 gram of tobacco) into a cigarette paper wrapper. The approximate weight of the cigarette wrapper was 60 milligrams. Control cigarettes containing about 0.90 gram of the Bugler tobacco per cigarette were prepared. Also made up were cigarettes containing 100 parts by weight of tobacco and 10 parts by weight of alumina produced by calcining aluminum tartrate at 1400° F. for 2 hours. All cigarettes were conditioned at 24° C. and 58% R.H. before smoking.

All cigarettes were mechanically smoked by the method described in detail in Industrial and Engineering Chemistry, vol. 28, No. 7, in an article entitled "Nature of Cigarette Smoke—Technique of Experimental Smoking,"

25 J. A. Bradford et al., pp. 836-839 (1936).

Cigarettes were smoked individually employing a constant puff of about 2 seconds' duration once each minute and with sufficient puffs to leave a butt of about 22 mm. The smoke from 5 cigarettes of a given composition was 30 collected in a glass-wool trap packed to give about 40 cm. water pressure drop at a flow rate of 1050 cc. of air per minute. This trap was shown to collect at least 95% of the nonvolatile components of the smoke. The trap was 35 evacuated for 20 minutes and weighed. The weight increase divided by 5 was reported as the milligram of tars per cigarette.

The results reported in the accompanying table represent the average of three determinations, each determination 40 representing the result of smoking 5 cigarettes of the reported composition.

These results show that the alumina produced by thermal decomposition of aluminum acetate was highly effective in reducing cigarette tars, whereas the alumina 45 similarly produced by thermal decomposition of aluminum tartrate had a much smaller effect on total tars.

Similar smoking tests were conducted using alpha-alumina trihydrate in the amounts of 5% and 10% of the tobacco weight and activated bauxite (chiefly an amorphous pure alumina) in the amount of 5% of the tobacco weight. It was found that the activated bauxite reduced 50 total tars by only 2% and that 5% and 10% of alpha-alumina trihydrate actually increased the tars by 11% and 2%, respectively.

*The Effect of Mixing Finely Divided Aluminas Produced
by Ignition of Organic Aluminum Salts With Cigarette
Tobacco on the Total Tar Content of Cigarette Smoke*

Composition of Cigarette	Av. Wt. of Cigarette, gm.	Av. Pressure Drop During Smoking, cm. H ₂ O	Av. No. of Puffs	Av. Butt Length, mm.	Av. Tars Per Cigarette, mg.	Percent Tar Reduction
Control Cigarette (no alumina)	0.9464	4.5	9.4	21.9	34.9	-----
Cigarette Containing 10% ¹ Alumina from Ignited Basic Aluminum Acetate ²	1.0222	5.4	8.5	22.5	27.5	21.5
Cigarette Containing 10% ¹ Alumina from Ignited Aluminum Tartrate ³	1.0237	5.3	9.6	20.9	32.7	6.3

¹ Based on weight of tobacco.

² Basic aluminum acetate ignited at 1400° F./2 hr.

³ Aluminum tartrate ignited at 1400° F./2 hr.

tests were conducted to show the behavior of other aluminas with the same tobacco.

Basic aluminum diacetate, $Al(OH)(C_2H_3O_2)_2$, was placed in a muffle furnace held at 1400° F. for 2 hours.

I claim:

1. A smoking mixture comprising tobacco shreds having uniformly mixed therewith a small quantity of the finely divided high surface area alumina produced by

thermal decomposition of a basic aluminum acetate in an oxidizing atmosphere at a temperature and for a time sufficient to oxidize completely hydrogen and carbonaceous matter therein into volatile combustion products.

2. A cigarette containing the smoking mixture of 5 claim 1.
